UNITED STATES PATENT OFFICE.

JAMES R. MILLER, OF McRAE, GEORGIA.

AUTO VALVE GRINDER.

1,402,081.

Specification of Letters Patent. Patented Jan. 3, 1922.

Application filed December 18, 1919. Serial No. 344,681.

To all whom it may concern:

Be it known that I, JAMES R. MILLER, a citizen of the United States, residing at McRae, in the county of Telfair and State of Georgia, have invented a new and useful Auto Valve Grinder, of which the following is a specification.

The device forming the subject matter of this application is a valve grinder, wherein the shaft which turns the valve, is mounted for longitudinal sliding movement, and one object of the invention is to provide novel means whereby, at will, longitudinal movement may be imparted to the shaft, in addition to the normal rotatory movement through which the grinding is brought about. Another object of the invention is to provide a tool of the sort mentioned which will hold a detached valve cage, as distinguished from securing the tool to the engine, or operating the tool upon the engine, thereby to grind the valve in situ.

In the accompanying drawings:—

Figure 1 is a front elevation of my improved auto valve grinder.

Figure 2 is a vertical sectional view taken on the line 2—2 of Figure 1 and looking in the direction indicated by the arrows.

Figure 3 is a horizontal cross sectional view taken on the line 3—3 and looking downwardly in the direction indicated by the arrows portions of the manually actuated rack bar being omitted, and

Figure 4 is a bottom plan of the device.

The valve grinder includes a frame, comprising parallel side members 10 and 11, connected at one end by a screw 12 supporting a handle 13, spacing the members 10—11.

Disposed below the handle 13 and connecting the side members 10 and 11 are transverse supports or plates 14 and 15, which render the frame rigid at its upper end. The plates 14 and 15 are provided respectively, with bearing sleeves 16 and 17, in which is journaled a vertical shaft 18 having at its lower end an enlarged portion 19 provided with a socket 20. The upper end of the shaft 18 is surrounded by an expansible helical spring 24 which engages an abutment or nut 25 on the upper end of the shaft, and bears against the plate 14, so as to exert upward thrust on the shaft 18, for a purpose to be hereinafter explained. The pressure exerted by the spring 24 against the shaft 18, can be regulated by means of the adjusting nut 25.

Vertically slidable in the plates 14 and 15 near the side member 10, is a plunger 26 preferably of rectangular cross section and operating through aligned vertical openings 27 in the plates 14 and 15, the plunger being limited in its upward movement by a stop 28, shown in a form of a cotter pin engaged through an opening in the lower end of the plunger beneath the plate 15, and limiting the movement of the plunger in an upward direction by contact with said plate. The plunger 26 is provided with an inwardly extended arm 29 flattened on the bottom to engage the upper end of the shaft 18. The shaft 18 rotates in contact with the arm 29. The plunger 26 is normally elevated by the action of the spring.

On the shaft 18 is fixed a pinion 31 which is horizontally disposed between the plates 14 and 15. Vertically mounted in horizontally spaced relation at either side of the plunger 26 and located on the side member 10, are two bearing plates 32, each provided with an inverted L-shaped opening or slot 33 having a vertical extension 34, said slot receiving for sliding movement, a manually operated rack bar 35 which is provided at one end with a handle 36. The rack bar 35 is designed to be reciprocated in the slots 33 having a vertical extension 34, and is provided with a longitudinal rib 37 received in the extension 34 of the slot 33, and guiding the rack bar during its reciprocation. Since the teeth 38 of the rack bar 35 terminate short of the ends of the rack bar, as shown at 41, the maximum length of the stroke of the rack bar is determined. The lower face of the rack bar 35 at its free end is provided with a cam rib 39 which is adapted to enter the lower portions of the slots 33. The plunger 26 is provided with a vertical recess 40 of greater length than the combined thickness of the rack bar 35 and the cam rib 39, and as the rack bar is drawn inwardly, the cam rib 39 engages the shoulder formed by the bottom edge of the recess 40 and thereby cause the plunger to be moved downwardly. Since the arm 29 of the plunger 26 engages the upper end of the shaft 18, the shaft will be moved downwardly against the action of the spring 24, thereby to unseat the valve, from its seat as will be described herein-after.

The side members 10 and 11 carry, respectively, inwardly projecting jaws 42 and 43 near their lower ends, the jaws 42 being

located in spaced relation on the side member 10 and the jaw 43 being located on the side member 11 in staggard relation intermediate of the jaws 42. All of said jaws 5 are provided with concaved inner faces, so as to receive valve cage 44 of the usual type, the valve stem appearing at 45. The valve stem 45 is provided with an opening 46 and the socketed member 19 is provided 10 with an alined opening for receiving a cotter pin 47 or the like, whereby the valve stem can be coupled to the shaft 18. The cage 44 is held between the jaws 42 and 43, the lower extremities of the side 15 members 10 and 11 being resilient for movement toward and away from each other. The ends of the members 10 and 11 are received in a resilient loop 48, said loop having parallel end portions 49, one of which 20 is split, and outwardly convexed side portions 50 adapted to accommodate the cage 44 of the valve 51. The valve 51 is held by the spring 24 in frictional engagement with its seat. When the rack bar 35 and 25 the pinion 31 impart rotation to the shaft 18, the valve 51 will be oscillated and by the application of abrasive material between the valve and its seat, foreign matter will be removed and the valve ground. The application 30 of the abrasive material is facilitated by reason of the unseating of the valve 51 through the medium of the cam rib 39 and the shoulder at the lower end of the recess 40 in the plunger 26, these elements causing 35 the shaft 18 to move downwardly against the action of its spring 24, arm 29 bearing on the shaft. This operation also serves to dislodge and permit the discharge of any particles which have been removed from 40 the valve or its seat. It will be understood that the device can be operated while the workman is maintaining a substantially erect posture. The valve cage 44 is clamped in position by means of a binding screw 52 45 which is threaded into one of the side portions 29 of the loop 48 and contacts with the side member 11 of the frame, thus forcing the jaws 42 and 43 to grip the cage. The cage 44 can be adjusted vertically between the jaws 42-43, so that when the 50 device is operated, the valve 51 will be seated on the cage. In order that the tool will not slip when in use, the lower extremities of the side members 10 and 11 are 55 formed with projecting points 53. The tool is held in the left hand through the medium of the handle 13 and the points 53 afford a hold upon a work bench. It is to be understood that when the device is being used to grind 60 a valve, the rack bar 35 is not shifted sufficiently so that the cam rib 39 will cause the unseating of the valve. The valve is un-

seated only when it is desired to insert grinding compound. By backing off the screw 52 and pulling the cotter pin 47, the cage and its valve can be readily removed from the tool.

I claim—

1. In a valve grinding and reseating tool, a frame, means for supporting the frame against movement, holding means for the frame, clamping means carried by the frame and operated therebetween in conjunction with the frame, said clamping means being designed to hold a valve cage provided with a valve seat, a valve head and a spindle on a valve head rotatably carried by the cage, a shaft journaled vertically in the frame, means to limit the shaft in one direction, a socket at one end of the shaft for coupling the same to the valve stem, spring means coacting between the frame and the shaft, to hold the valve against its seat under tension, a pinion on the shaft, a rack bar slidabale in the frame and engageable with said pinion, said rack bar being provided with means whereby it may be reciprocated, a plunger slidabale in the frame and engaging one end of the shaft, said shaft being held in contact with the plunger, and means cooperative between the rack bar and plunger whereby the latter may be shifted at the limit of the stroke of the rack bar to shift the plunger whereby to shift the shaft for unseating the valve.

2. In a valve grinder, a frame; a shaft journaled in the frame and movable longitudinally therein; a pinion on the shaft; a rack bar slidabale in the frame and meshing with the pinion; a plunger mounted for reciprocation in the frame and forming an abutment for the shaft; and interengaging elements on the rack bar and on the plunger cooperating to impart longitudinal movement to the shaft when the rack bar is reciprocated beyond a predetermined point.

3. In a valve grinder, a frame; a shaft journaled in the frame and movable longitudinally therein; a pinion carried by the shaft; a rack bar slidabale in the frame and meshing with the pinion; a plunger slidabale in the frame and forming an abutment for the shaft; and a cam rib on the rack bar and coacting with the plunger to impart longitudinal movement thereto and to the shaft, when the rack bar is moved beyond a predetermined point.

In testimony that I claim the foregoing as my own, I have hereto affixed my signature in the presence of two witnesses.

JAMES R. MILLER.
